UNITED STATES PATENT OFFICE.

EDWARD C. SIQUEIRA, OF OAKLAND, CALIFORNIA.

CHANGE-MAKING MACHINE.

1,327,969.

Specification of Letters Patent. Patented Jan. 13, 1920.

Application filed March 8, 1917. Serial No. 153,524.

To all whom it may concern:

Be it known that I, EDWARD C. SIQUEIRA, a citizen of the United States, residing at Oakland, in the county of Alameda and State of California, have invented certain new and useful Improvements in Change-Making Machines, of which the following is a specification.

This invention relates to improvements in coin collecting and dispensing handling apparatus and more particularly to a device for making change. The present application is an improvement of my copending application Serial Number 43,051, filed

15 Aug. 2, 1915.

The principal object is to provide efficient mechanism which by the mere movement of a suitable lever, a plurality of coins will be ejected which are equal in value to a coin 20 of larger denomination.

Another object of the invention is to arrange the coin holding tubes, that the coins from the registering mechanism fall directly into these tubes from the inside of the housing, and yet the tubes are open at the top to permit other coins being placed therein 25 from the outside.

With these and other objects in view the invention consists of certain novel features 30 of construction, combination and arrangements of parts herein illustrated and more specifically pointed out in the appended claims.

To more fully comprehend the invention 35 reference should be had to the drawings forming a part of the specification and wherein:

Figure 1 is a view in perspective of the device as viewed from the front.

40 Fig. 2 is a view in perspective as viewed from the rear.

Fig. 3 is a view in front elevation with the cover plates removed.

Fig. 4 is a sectional plan view on the line 45 4—4 in Fig. 3.

Fig. 5 is a view in section on the line 5—5 Fig. 4.

Fig. 6 is a view in plan of the ejecting mechanism below the coin tubes.

50 Referring to corresponding parts in the several views by the same numerals of reference: 1 denotes a base from the sides of which rise a housing consisting of the side plates 2, the front plate 3, and a top 4.

55 About midway up the front of the housing a

shelf 5 is formed by the plate 6 which contains openings 8 through which coins may be deposited by hand. Surmounting the top of the housing is a coin receptacle 9 into which the coins are deposited and from 60 which they pass to the registering and assorting mechanism denoted in general by 12. As this mechanism forms no part of my present invention and is fully described in my copending application Serial #153,525, 65 filed Mar. 8, 1917, I have not deemed it necessary to describe the same in detail. It is sufficient to say that as the coins are registered they drop through certain openings in the plate 13, onto the chute 14 or 15 according to value. These chutes are mounted on the rod 16 and they may be shifted laterally, the upper ends being of sufficient width to remain under openings heretofore mentioned, while the lower ends are brought adjacent the coin receiving tubes hereinafter described.

In the machine illustrated, the coin tubes just mentioned are six in number and while I have assigned certain values to the coins 80 which are contained in the various tubes it will be understood that other values and arrangements of tubes may be used. As herein illustrated the tubes on the left of the machine as viewed in Fig. 3 and denoted 85 by 18 are both of the same size and adapted to receive five-cent pieces. The next two tubes denoted by 19 are for dimes, while the fifth and sixth tubes from the left denoted by 20 and 21 respectively are for twenty-five cent and fifty cent pieces respectively.

The ends of these tubes are attached to the upper and lower plates 22 and 23 respectively and it will be noted that the upper plate is positioned a sufficient distance below plate 6 to allow the coins which fall down the chutes to slide over this plate into the coin tubes. Below the plate 23 is a plate 24 having certain recesses 25 arranged transversely of the plate and the depth of 100 which are that of the respective coins for which they are adapted. These recesses are equal in number to the coin tubes, are positioned directly under the same and have a width slightly greater than the diameter 105 of the openings in these tubes.

From the front edge of plate 24 extend certain slots 26 to a point approximately under the center of the largest coin tubes and it will be noted that the rear points of 110

the tubes are in alinement. Longitudinally disposed under the plate 25 is a vertical supporting member 27 and in plate 24 back of this supporting member are provided 5 openings 28 that are slightly larger than the respective openings of the tubes associated therewith. It will also be noted that the rear position of these openings 28 are in alinement.

10 Slidably mounted in the recesses 25 are certain plates 30 which have openings 31 the exact size of the coin tubes positioned thereabove and these openings are adapted to be positioned directly under the opening 15 of the coin tubes when the plates are in their forward position. It will be noted that the openings in the plates 30 and those in the plate 24 intersect more or less, the amount of intersection of the larger openings 20 being greater than those having smaller openings so that the same amount of movement will cause any of the various openings in plate 30, to coincide with the corresponding opening 28 in plate 24. The sliding 25 plates 31 have formed on the underside certain arms 35 which project downwardly through the slots 26 heretofore mentioned and contacting with these arms and tending to urge the same forward are springs 36.

30 Mounted in the side plates 37 is a shaft 38 on which is pivotally mounted certain operating bell crank levers 39. The longer ends 37' of these levers extend through vertical slots in the front plate 3 and are there 35 provided with suitable buttons 40, containing numbers to designate the amount of change which the pressing of that lever will eject. Between the lower ends of side plates 37 is a shaft 41' on which is pivotally mounted 40 a number of U-shaped operating members 41, 42, 43 and 44. The shorter arms 45 of the bell crank extend downwardly and have mounted in their ends rollers 46, which rollers are adapted to contact with the front 45 faces of the various members 41 to 44 inclusive.

It will be noted that member 44 contains a lug 47 which overlaps member 43, and 43 in turn is provided with a lug 48 which overlaps member 42. Thus when the end 50 right hand member 44 is operated, the members 43 and 42 will also be moved.

It will be noted that bell cranks, the buttons of which are marked 10, 25, 50 and 100 55 have their shorter arms contacting with the U-members 41, 42, 43 and 44 respectively. The upper ends of the members 41 to 44 are arranged to contact with the various arms 35. Member 41 it will be seen contacts with 60 the arms 35 on both of the plates associated with tubes 18. The member 42 makes contact with the arms of the sliding plates 30 associated with tubes 19 and also with the arm associated with the tube 18 adjacent 65 the tubes 19. Members 43 and 44 contact

only with the arms of the sliding plates of tubes 20 and 21 respectively. Positioned back of the division wall 27 and under the openings 28 is an inclined chute 50 which extends rearwardly to an opening 51 in the 70 rear wall of the housing. On the outside of the latter is a receptacle 52 from which the coins may be easily taken.

In order to accurately position these various plates and consequently the openings in 75 the slides with respect to the openings in the tubes I provide adjusting screws 53 and 54, the former being used to adjust the plates 42, 43, and 44 while the latter is used to adjust plate 41.

Having thus described the various parts 80 of my invention, the manner in which it is operated is as follows:

If ten cents is received and it is desired to give the patron two five-cent pieces in return, the dime is deposited in one of the coin tubes 19 and the bell crank marked 10 is depressed. This rotates member 41, the upper edge of which contacts with the depending arms 35 on the sliding plates 30 90 under tubes 18. Now if the openings in these sliding plates are of just the size and thickness of a coin it follows that if there is a supply of coins in the various tubes that the lowermost ones will rest within 95 these openings. Hence when the bell crank is depressed these plates will move rearwardly and the coins which are in the openings 31 will be moved over the openings 28, through which they will fall onto the chute 100 50, and slide by gravity into the receptacle 52.

In a like manner if change for twenty-five cents is required, the correspondingly numbered bell crank is depressed, which will 105 operate the sliding plates 30 under the two tubes 19 and the adjacent plate under one of the tubes 18, and thus be ejecting two dimes and one nickel. If a dollar's worth of change is to be ejected the correspondingly 110 marked lever is depressed which moves the member 44 and through the lug 47 the member 43, which in turn through the lug 48 attached thereto moves the member 42. The movement of these various members move 115 the plates 30 associated therewith, and there is ejected a coin from one of the tubes 18, from the two tubes 19 and from tubes 20 and 21. As here illustrated fifty cents, twenty-five cents, two dimes and a nickel making 120 one dollar in change.

The coins as they are ejected fall onto the chute 50 and slide down into the receptacle 52 placed on the opposite side of the device, within easy reach of the patron. 125

While I have shown the preferred embodiment of my invention it will be understood that changes in minor features of design and details of construction within the scope of the claims may be resorted to 130

without sacrificing any of the advantages thereof.

I claim:

- 5 1. A device of the character described comprising two tubes for coins of lowest denomination, two for the first multiple thereof, and one each for the higher multiples thereof, sliding plates positioned under said tubes and having openings adapted to register with said tubes and withdraw therefrom one coin at a time, depending arms formed in said plates, pivotally mounted members adapted to coöperate with said arms and move said plates, means for operating said members, lugs formed on the pivotal members corresponding to the higher multiples adapted to overlap the members of lower multiples but not the members corresponding to the lowest denomination.
- 10 2. A device of the character described comprising two tubes for coins of the lowest order, two tubes for coins of the first multiple thereof and one tube for each of the higher multiples thereof, sliding plates positioned under said tubes and having openings adapted to be brought into alignment with said tubes and withdraw one coin at a time, a pivotally mounted member adapted to move the plate of the tubes of
- 15 the first multiple and one of the plates of

lowest order, like members for moving the plates of higher multiples, lugs on said members of higher multiples overlapping those of lower multiples, and means for operating said members.

35

3. A device of the character described comprising a plurality of receiving tubes for coins of lowest order, a plurality of receiving tubes for coins of the first multiple order, a single coin receiving tube for coins of higher multiples, a sliding plate positioned under each of said tubes and having a coin receiving opening adapted to align with said tubes and withdraw one coin at a time, an arm extending outwardly from each of said plates, a pivotally mounted member having its free end contacting with the plate arms of the tubes of lowest order, a similar member having its free end contacting with the plate arms of the tubes of the first multiple, and like members contacting each with the plate arms of higher multiples and lugs on the said members of the higher multiples, said operating member of the first multiple and each of the members of higher multiples being overlapped by the lug of next higher order, and means for operating said members.

40

In testimony whereof I affix my signature.

EDWARD C. SIQUEIRA.
